UNITED STATES PATENT OFFICE.

GROVER C. SINGER, OF OAKLAND CITY, INDIANA.

PORTABLE COAL TIPPLE.

Application filed July 22, 1924. Serial No. 727,526.

This invention relates to portable coal tipples especially designed for use with surface mining equipment.

In the art of surface mining in which the present invention is used the dirt and rock constituting the overburden are stripped away or removed from the top of the coal by means of a large steam shovel and the coal is then dug up with a small steam shovel and thrown into small railway cars and hauled to a coal tipple, wherein it is graded or classified for shipment.

The present invention aims to obviate the necessity of providing the large and expensive stationary plant now used for grading or classifying the coal and also to obviate the necessity of the intermediate haul of the coal from the point at which the surface mining is being carried on to the point, at which the tipple is located, the coal being graded or classified at the place where it is mined and being directly loaded into the cars utilized for shipping the same.

A further object is to provide a portable coal tipple which may be readily moved from place to place with the surface mining equipment as the mining operation progresses.

A still further object is to provide a portable coal tipple of this character and in which the classifying or grading and the loading operations are carried out continuously and in a novel and efficient manner.

Other objects and advantages of the invention reside in certain novel features of the construction, combination and arrangement of parts which will be hereinafter more fully described and particularly pointed out in the appended claims, reference being had to the accompanying drawings forming part of this specification, and in which:—

Figure 1 is a fragmentary diagrammatic view, partly in side elevation and partly in vertical section, showing a portion of an apparatus embodying the present invention;

Figure 1^a is a view similar to Figure 1 of an adjacent portion of the same apparatus;

Figure 1^b is a view similar to Figures 1 and 2, showing the remaining portion of the apparatus illustrated in Figures 1 and 1^a;

Figure 2 is a fragmentary perspective view, showing the separate compartments

for the nut and slack and the means employed for swinging the boom;

Figure 3 is a diagrammatic view in side elevation showing the manner of controlling one of the longitudinally shiftable loading conveyors;

Figure 4 is a fragmentary view in plan, illustrating the separate elevators and conveyors employed for the nut and slack;

Figure 5 is a detail perspective view of one of the shaker screens;

Figure 6 is a detail view in side elevation of one of the loading conveyors;

Figure 7 is a view thereof in transverse section on line 7—7 of Figure 6;

Figure 8 is a detail perspective view of the shaker screen employed in separating the nut from the slack;

Figure 9 is a similar view of the shaker screen employed for separating the egg from the nut and slack; and

Figure 10 is a detail view in transverse section on line 10—10 of Figure 4.

Referring to the drawings it will be understood that the present invention is designed for use with the usual surface mining equipment which is well known to those skilled in the art and needs no detailed explanation. In accordance with the usual practice after the overburden has been removed a single railway track 10 is laid on the coal to be dug up. Only the single track 10 is employed for the reason that it must be shifted about to permit the mining of all the coal. The present invention proposes in general the use of a portable coal tipple, designated generally at T which may be self propelled or which may be moved about in any suitable manner on the track 10, and in conjunction with the tipple T a number of railway cars, designated at 11, 12, 13 and 14 are employed, the cars 11, 12, 13 and 14 being the ordinary cars used for tipping or transporting the coal to the point of use or storage. The portable coal tipple T may not only be moved about on the track 10 during the mining operation in any particular locality but may also be moved from one locality to another, thereby avoiding the very serious loss resulting from the abandonment or wrecking of the large stationary plants now in use as well as eliminating the expense of the intermediate haul from the point at which the coal is mined to the stationary tipple.

105
110

The portable coal tipple T which constitutes the present invention comprises a wheeled platform 16 which may take the form of an ordinary railway car and which runs on the track 10. On one end of the platform 16 a power plant 17 is arranged and may utilize a steam boiler and an engine to drive the generator employed for generating the electricity utilized to drive the various instrumentalities of the tipple or an internal combustion engine may be employed for this purpose. It is also to be understood that the wheeled platform 16 may be self propelled by means of suitable electric motors or other means or may be hauled or drawn about as desired.

Adjacent the power plant 17 the wheeled platform 16 is provided with a hopper 18 into which the coal is dumped as mined from the steam shovel S. An elevator 19 is employed to carry the coal from the hopper 18 to the upper of a series of classifying screens, designated generally at 20, and hereinafter more fully described.

The elevator 19 is rotatably supported in a conventional manner on a frame 21, the frame 21 being secured at its lower end to the wheeled platform 16 and being connected at its upper end to a pair of masts 22.

It is to be understood of course that the elevator 19 is of conventional construction and is electrically driven in accordance with the usual practice.

The shaker screens 20 constitute the means for classifying or grading the coal, and in the embodiment illustrated three shaker screens are employed and are arranged one above the other, there being a top screen, designated generally at 23 for separating the block coal from the egg, nut and slack, a middle screen 24 for separating the egg from the nut and slack, and a bottom screen 25 for separating the nut from the slack.

As shown in Figure 5 the shaker screen 23 includes a frame having tracks 26. The screening element consists of a metallic plate 27 having perforations 28 admitting of the passage of all sizes of coal except the block size. This screening element 27 is mounted for reciprocatory movement on the tracks 26 by means of rollers 29 carried by axles 30 provided on the plate 27. The track 26 may consist of angle irons as shown although channel irons might be employed to afford a more positive drive if found desirable.

Means is employed for imparting reciprocatory movement to the plate 27 and may comprise an electric motor 31 with which gearing 32 is associated which drives a wheel 33 fixed to a shaft 34 rotatably mounted in bearings 35 and extending transversely below the upper end of the screen 23. A disk 36 is also fixed to the shaft 34 and the wheel 33 and disk 36 carries crank pins 37 between the electric motor 31 and the end

which are operatively engaged with connecting rods 38, the latter being also pivotally connected to arms 39 fixed to and extending laterally from the screening element or plate 27.

The screening elements of the shaker screens 24 and 25 are similarly mounted and reciprocated.

At its lower end the screening element 27 is formed with an imperforate extension 40 providing a chute for delivering the block coal onto a loading conveyor designated generally at 41 and mounted for longitudinal movement or adjustment on a boom designated generally at 42.

The boom 42 is made of structural steel and is of rectangular tubular form. As shown in Figure 2, the boom is supported on one end of the wheeled platform 16 by means of a bearing plate 43 suitably fixed to the platform 16 and serving as a mounting for a rotatable plate 44 pivotally connected by means of a pin 45 to the plate 43. The plate 44 is secured to the boom 42. An electric motor 46 drives the plate by means of worm gearing 47. With this arrangement the boom 42 is mounted for swinging movement in a horizontal plane so that slight curvature in the track 10 may be taken care of. In addition to the supporting means thus provided for the boom 42 a plurality of guy lines 50 extend between the masts 22 and various points along the boom. These guy lines 50 may be separate elements or they may be composed of a single cable trained over pulleys 52 carried by each mast and pulleys 53 mounted on the boom and then wound on a drum 54 controlled from a motor 55 by means of gearing 56. Of course such a cable 50 is provided on each side of the boom, there being one cable for each mast 22, and there being a set of pulleys 52 and 53 for each cable.

The conveyor 41 is shown to advantage in Figures 6 and 7 and comprises a main frame 57 and a pivoted section 58. The main frame 57 includes fixed side bars 59 and the pivoted section 58 includes pivoted side bars 60, and these side bars 59 and 60 carry rollers 61 and 62 around which the endless conveyor element 63 runs. As shown to advantage in Figure 6 the pivoted bars 60 are arranged at one end of the fixed bars 59 and are pivotally connected to these fixed bars. The inclination of the bars 60 with respect to the bars 59 is controlled by means of a cable 65 having one end connected to the pivoted sections 58 and having its other end wound about the winding drum 56 controlled by an electric motor 67 mounted on the main frame 57. The endless conveyor element 63 may be driven in either direction by means of an electric motor 68 and gearing 69 between the electric motor 68 and the end

roller 70 over which the conveyor element 63 is trained.

The conveyor 41 is mounted on the boom 42 for longitudinal movement in either direction by means of wheels 71 rotatably mounted on axles 72 carried by the main frame 67 of the conveyor, the wheels 71 running on tracks 73 provided on the boom 42.

Means is employed for positively moving the conveyor 41 in either direction along the tracks 73 and as shown to advantage in Figure 3 it may comprise a cable 74 having one end connected as at 75 to one end of the conveyor 41, the other end of the cable 74 being wound on a winding drum 76 driven by an electric motor 77. Intermediate its ends the cable 74 is trained over guide sheaves 78. A second cable 79 is also provided and has one end connected as at 80 to the end of the conveyor 41 opposite to the connection 75 of the cable 74, the other end of the cable 79 being reversely wound on the drum 76 and the intermediate portion of the cable 79 being trained over guide sheaves 81. With this arrangement when the winding drum 76 is rotated in one direction as for instance in a counter-clockwise direction, as viewed in Figure 3 the cable 74 will be wound on the drum 76 and the cable 79 will be paid out whereby the conveyor 41 is moved to the right as viewed in Figure 3. Rotation of the winding drum 76 in a clockwise direction causes the cable 79 to be wound on the drum 76 and the cable 74 to be paid out and consequently result in the movement of the conveyor 41 to the left, as viewed in Figure 1. By virtue of this movement and control of the conveyor 41 the block coal which slides onto the conveyor from the chute 40 may be loaded into the car 12 along the entire length of the car, and as the swinging section 58 may be moved upwardly or downwardly within limits the level at which the block coal is delivered to the car 12 may be varied.

The egg, nut and slack fall through the perforations 28 of the screening element 27 of the shaker screen 23 onto the screening element 85 of the shaker screen 24, the said shaker screen 24 being disposed immediately below the shaker screen 23. As shown to advantage in Figure 9, the shaker screen 24 includes a screening element 86 made up of a metallic plate having apertures 87 of such size as to admit of the passage of nut and slack therethrough. Like the screening element 27, the screening element 86 is inclined. At its lower end the screening element 86 is formed with a central ridge or deflector 88 designed to deflect the egg coal into chutes 89 formed at the sides of the lower end of the screening element and terminating in inwardly directed extremities 90 which project into the boom 42 and deliver the egg coal onto a loading conveyor designated

generally at 91. The conveyor 91 is identical in construction with the conveyor 41 and is mounted on the boom and driven and controlled in exactly the same manner as the conveyor 41, the conveyor 91 serving to load the car 11 with egg coal. It is to be noted that the upwardly deflected ridge 88 and the spaced chutes 89 afford the necessary clearance for the conveyor 41. Of course the chute 40 is of sufficient length to accommodate the major portion of the movement of the travelling or movable conveyor 41.

The nut and slack coal which fall through the openings 87 of the screening element 86 drop onto the screening element 95 of the shaker screen 25. As shown to advantage in Figure 8 the screening element 95 also comprises a metallic plate having openings or perforations 96 admitting of the passage of the slack therethrough but too small to permit the nut to fall through the screening element. The nut coal slides down the screening element 95, which is also inclined, and then passes out through a lateral chute 97 formed at 98 the lower end of the screening element and serving to carry the nut coal over one side of the boom 42 and into a compartment 98 provided therefor in the wheeled platform 16 as shown to advantage in Figure 2. The slack which drops through the opening 96 falls onto an inclined deflecting apron 99 riveted to the underside of the screen 95 and serving to deflect the slack across the boom 42 and into the compartment 100 provided on the wheeled platform 16. An elevator 101 carries the nut coal from the compartment 98 up onto a conveyor 102 carried by the boom along one side of the top thereof. Similarly an elevator 103 carries the slack from the compartment 100 up to a conveyor 104 provided along the top of the boom 42 on the opposite side of the boom from the conveyor 102, as shown to advantage in Figure 4.

The conveyor 102 delivers the nut coal into the car 14, and this car 14 being the end car may be shifted to load the car throughout its length. Of course if found desirable a travelling conveyor, similar to the conveyors 41 and 91 may be employed on the boom in conjunction with the conveyor 102 if found desirable. Moreover lateral chutes or conveyors may be employed at the delivery end of the conveyor 102 if the same should be found desirable. Such a chute is designated at 105 in Figure 1.

The conveyor 104 delivers the slack onto a conveyor 110 having its frame provided with wheels or rollers which run on tracks on the boom in the same manner as the conveyors 41 and 91. The conveyor 110 does not however include any swinging section but it is proposed to drive the endless element of the conveyor 110 in either direction

by simply reversing the electric motor 111 which drives the conveyor 110 through gearing 112. The conveyor 110 is shifted longitudinally in either direction by means of a 5 motor actuated drum 113 and a pair of cables 114 reversely wound on said drum and connected to the opposite ends of the frame of the conveyor 110, the intermediate portions of the cable 114 being trained over 10 guide sheaves 115. By shifting the conveyor 110 longitudinally and driving the conveyor so as to cause it to deliver the slack coal first from one end and then from the other the car 13 may be loaded for its entire 15 length.

With this arrangement the coal is taken as it is mined and at the place where it is mined and is graded or classified and the classified products are immediately loaded 20 into individual cars ready for shipment to the point of use or storage. In this manner the intermediate haul of the coal as mined from the point at which it is mined to the stationary plant at which it is graded is 25 eliminated. Moreover the coal is directly loaded after the grading in such a novel and efficient manner as to occasion a minimum of handling and so as to permit of continuous operation. These advantages are 30 had and at the same time a portable tipple is provided which may be readily moved from place to place during the mining operation and from one locality to another.

I claim:—

35 1. A portable coal tipple for use with surface mining equipment including a single railway track and a train of cars thereon designed to receive the classified products from the tipple and comprising a series of shaker screens for classifying and segregating the coal into various grades, an elongated boom extending along and over the cars of the train, means for supporting the boom, and a plurality of loading conveyors mounted one above the other on the boom and extending longitudinally thereof, different loading conveyors receiving the different classified products of the screens, different conveyors being of different length 40 and discharging into different cars of the train so as to simultaneously load the cars of the train with the classified products.

50 2. A portable coal tipple for use with surface mining equipment including a single railway track and a train of cars thereon designed to receive the classified products from the tipple and comprising a series of screens for classifying and segregating the coal into various grades, an elongated boom 55 extending along and over the cars of the train, means for supporting the boom for turning movement about a vertical axis, controllable means for turning the boom, and a plurality of loading conveyors mounted 60 one above the other on the boom and ex-

tending longitudinally thereof, different loading conveyors receiving different classified products of the screens, different conveyors being of different length and discharging into different cars of the train so as to simultaneously load the cars of the train with the classified products.

3. A portable coal tipple for use with surface mining equipment including a single railway track and a train of railway cars thereon designed to receive the classified products from the tipple and comprising a wheeled platform running on said track in end to end relation with respect to said train and having a hopper designed to receive the coal as it is mined, a series of screens, means for supporting the screens on the wheeled platform above the hopper, an elevator for carrying the coal from the hopper to the series of screens, an elongated boom mounted on the wheeled platform and extending along and over the cars of the train, and a series of loading devices carried by the boom and receiving the classified products of the shaker screens and conveying such products separately to different cars of the train.

4. A portable coal tipple for use with surface mining equipment including a single railway track, a train of cars thereon designed to receive the classified products from the tipple and comprising a series of screens for classifying and segregating the coal into various grades, an elongated boom extending longitudinally along and over the cars of the train, means for supporting the boom, a plurality of loading conveyors, means for mounting the conveyors one above the other on the boom for longitudinal adjustment relative thereto, said conveyors extending longitudinally of the boom, independent means for controlling each loading conveyor and for shifting the same longitudinally of the boom, different loading conveyors receiving different classified products from the screens, different conveyors being of different lengths and discharging into different cars of the train so as to simultaneously load the cars of the train with classified products.

5. A portable coal tipple for use with surface mining equipment including a single railway track, a train of cars thereon designed to receive the classified products from the tipple and comprising a series of screens for classifying and segregating the coal into various grades, an elongated boom extending longitudinally along and over the cars of the train, means for supporting the boom, a plurality of loading conveyors, means for mounting the conveyors one above the other on the boom for longitudinal adjustment relative thereto, said conveyors extending longitudinally of the boom, independent means for controlling each loading conveyor

and for shifting the same longitudinally of the boom, different loading conveyors receiving different classified products from the screens, different conveyors being of different lengths and discharging into different cars of the train so as to simultaneously load the cars of the train with classified products, each of said conveyors having a vertically swingable section embodied therein, and means for controlling and swinging each of said sections.

6. In a portable coal tipple for classifying the coal consisting of a series of shaker screens arranged one above the other and including a screen for separating the block from the egg, nut and slack, a screen for separating the egg from the nut and slack and a screen for separating the nut from the slack, the screen for separating the block from the egg, nut and slack having an ex-

25 tension at its forward end constituting a chute, a loading conveyor receiving the block from said chute, the screen for separating the egg from the nut and slack having a central deflector at its forward end and also having extensions at the sides of its forward end providing a pair of chutes, said pair of chutes having inwardly directed extremities, a loading conveyor receiving the egg coal from the inwardly directed 30 extremities of said pair of chutes, the screen for separating the nut from the slack having an inclined and laterally directed chute at its forward end for the nut coal and also having an oppositely inclined deflecting 35 apron disposed below the same, and separate means for receiving the nut and slack from the laterally directed chute and from the apron respectively.

GROVER C. SINGER.
